(57) **CLAIM**

The ornamental design for a wearable thermometer for measuring temperature inside a person's clothes, as shown and described.

DESCRIPTION

FIG. 1 shows a front view of a wearable thermometer for measuring temperature inside a person's clothes;

FIG. 2 shows a rear view of a wearable thermometer for measuring temperature inside a person's clothes;

FIG. 3 shows a right-side view and left-side view of a wearable thermometer for measuring temperature inside a person's clothes;

FIG. 4 shows a top view of a wearable thermometer for measuring temperature inside a person's clothes;

FIG. 5 shows a bottom view of a wearable thermometer for measuring temperature inside a person's clothes;

FIG. 6 shows a bottom perspective view of a wearable thermometer for measuring temperature inside a person's clothes;

FIG. 7 shows a top perspective view of a wearable thermometer for measuring temperature inside a person's clothes.

The broken line showing of structural features is included for the purpose of illustrating non-claimed subject matter and forms no part of the claimed design.
